F. WILLIAMS

COMBINED PENCIL SHARPENER AND GUARD

Filed July 12, 1921

Inventor
Frank Williams.
By
Fuerstmann.

Attorney

UNITED STATES PATENT OFFICE.

FRANK WILLIAMS, OF HOT SPRINGS, SOUTH DAKOTA.

COMBINED PENCIL SHARPENER AND GUARD.

Application filed July 12, 1921. Serial No. 484,087.

To all whom it may concern:

Be it known that I, FRANK WILLIAMS, a citizen of the United States of America, and resident of Hot Springs, in the county of

5 Fall River and State of South Dakota, have invented certain new and useful Improvements in Combined Pencil Sharpeners and Guards, of which the following is a specification.

10 This invention relates to stationery and particularly to a pencil sharpener and holder, the said invention having for an object the provision of novel means whereby a sharpener is provided which may constitute a guard for the lead after the pencil is sharpened, or it may be employed as a means for retaining a pencil in a pocket to guard against loss of the pencil; and the said invention furthermore has for its object the

20 provision of a combined sharpener and guard constructed of a single piece of material having the characteristics and advantages stated.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

35 Figure 1 illustrates a view in elevation of a pencil, showing a device embodying the invention applied thereto;

Figure 2 illustrates a similar view of the opposite side of the pencil and guard;

40 Figure 3 illustrates a longitudinal sectional view of the device;

Figure 4 illustrates a perspective view of a clamping ring; and

45 Figure 5 illustrates a perspective view of the end and a fragment of the said device.

In these drawings 10 denotes a tubular body having a conical or tapered outer end 11. The body is slotted longitudinally from its inner end as at 12 and terminates in an 50 enlarged aperture 13. The purpose of the slot is to permit the expanding or flexing of the body so that it may be free to move under the influence of the clip or ring 14 which embraces the body near its inner end, 55 the said clip being of resilient material and preferably of slightly less diameter than the

body, in order that the clip may be spread to embrace or partially encircle the body to operate in pressing the body on the pencil 15 with sufficient force to frictionally retain 60 the body on the pencil. The body has an annular bead 16 near its inner end which constitutes an abutment for the clip to prevent its movement longitudinally of the said body. 65

The body is furthermore provided with longitudinally extending serrations or ribs 16' to insure a firm fingerhold when the body is being turned, as is done when a pencil is to be sharpened, as will presently appear. 70

The tapered or conical end 11 has a longitudinally extending slot 17 which forms a clearance for the escape of the cuttings during the sharpening operation, and the material of the body on one side of the slot is bent inwardly slightly and the edge is beveled or sharpened to produce a cutting blade which operates to sharpen the pencil. 75

The outer end of the body has an aperture 80 which is but slightly greater than the aperture of the lead of pencils now in ordinary use, and it is the purpose of the inventor that the lead shall project from the outer end of the body to expose the lead for use 85 when the pencil is manipulated, although, if desired, the pencil could be pulled inwardly slightly in order to conceal the lead within the area of the body, a condition which would result in protecting the lead 90 while it is not in use.

The body at the outer end is further provided with a resilient tongue 18 which spans the slot and overlies a portion of the body on the opposite side of the slot, the said 95 tongue acting to form a guard at the entrance to the slot to prevent the material from abrading a pocket or clothing while the pencil is being carried.

The inner end of the body has an integral 100 finger 19 which is intended to extend over a part of the pencil, and this finger is offset with relation to the surface of the pencil to form a clearance for the reception of the material forming the garment having a 105 pocket to which the pencil is applied, it being understood that the finger will bear against the outer surface of the material and press it against the pencil with a clamping action to prevent dislodgment of the 110 pencil from the pocket. The outer extremity of the finger is curved inwardly to form

a bead 20 to increase the frictional contact between the finger and the garment.

It has been found that a device made in accordance with this invention can be inexpensively manufactured and that it will prove efficient and satisfactory in the particulars enumerated.

I claim:

5 In a combined pencil sharpener and guard,
10 a body having a cylindrical portion with a

longitudinally extending slot at the inner end, the said body being tapered toward the outer end and provided with a longitudinally extending slot, the edge of the said slot being shaped to form a cutting blade, 15 a tongue extending from the body on one side of the slot and projecting over the said slot at the outer end of the said body, and means for retaining the body on a pencil.

FRANK WILLIAMS.
